UNITED STATES PATENT OFFICE.

EBERHARD SCHNEIDER, OF NEW YORK, N. Y.

REGISTERING DEVICE FOR A MOVING-PICTURE MACHINE.

1,156,934.

Specification of Letters Patent.

Patented Oct. 19, 1915.

Application filed October 22, 1907. Serial No. 398,579.

To all whom it may concern:

Be it known that I, EBERHARD SCHNEIDER, a citizen of the United States, residing in the borough of Manhattan, city, county, and State of New York, have invented a new and useful Improvement in a Registering Device for a Moving-Picture Machine, of which the following is a specification.

This invention relates to a registering device for moving picture machines. Its organization comprises means for adjusting the film of a moving picture machine relatively to the projecting aperture of the machine.

15 In the drawings Figure 1 represents a section as on the line 1, 1 of Fig. 2 viewed in the direction of the arrows of said Fig. 2 and with some parts in full; Fig. 2 shows a section as on the line 2, 2 of Fig. 1 with some 20 parts in full and Fig. 3 is a side view of the invention with some parts omitted.

A table is indicated at 9 upon which is supported a bed plate 15 that carries the front standard 16 and the rear standard 17. 25 A connecting brace 17^b connects the upper ends of the said standards 16 and 17. A rack 17^a is formed in the standard 17. A sleeve 18 is slidably carried on the standard 17 and has formed therewith the ears 18^a 30 and the journal lugs 18^b.

A spindle 18^c is journaled in the lug 18^b, and has fastened at one end thereof the band wheel 18^d. A pinion 18^e is fastened to the spindle 18^c and is located between the lugs 35 18^b. The pinion 18^e meshes with the rack 17^a. A spring 18^f is held in position by the screw 18^g. Plugs 18^h are fastened on the ends of the spring 18^f; pass through the sleeve 18 and bear against the standard 17, 40 by means of which the sleeve 18 is held in different positions. A hollow shaft 19 with the eccentric portion 37 is supported in the ears 18^a. A frame with the members 11 and 12 is hinged on the hollow shaft 19. Extensions 11^a and 12^a are formed respectively 45 with the members 11 and 12. A main shaft 13 is journaled in the extensions 11^a and 12^a. Links 14 have each one end supported on the shaft 13 with the other end pivoted to 50 the bed plate 15 by means of pivots 14^a. An extension 11^b extends from the extension 11^a and has fastened thereto one end of the spring 11^c. The other end of the said spring is fastened to the bed plate 15. An operating 55 crank 20 is carried on the main shaft 13, and a spur gear 21 is fastened to said

shaft. A shaft 23 is journaled in the members 11 and 12 and has fastened thereto a pinion 22 that meshes with the spur gear 21. A spur gear 24 is fastened to the shaft 23, 60 and a bevel gear 25 is fastened to the shaft 23. A substantially vertical shaft 27 is journaled in the member 12 and has fastened thereto the bevel gear 26 that meshes with the bevel gear 25. At the upper end of the 65 shaft 27 is fastened the bevel gear 28. A shaft 30 is journaled in the members 11 and 12 and has fastened thereto the bevel gear 29 which meshes with the bevel gear 28. A sprocket drum 5 is fastened to the shaft 30. 70 A frame 62 is pivoted to the member 11 by the pivot 63 and has journaled therein the presser rollers 61. A spring 64 has one end fastened to the member 11 at 65 and the other end thereof bears against the frame 75 62. The frame 62 has a slotted extension 66 by which it can be clamped to the member 11, by means of the screw 67 and the thumb nut 68. A shaft 32 has fastened thereto a pinion 31 which meshes with the spur gear 80 24. A disk 33 having a pin 34 and a bevel gear 55 are also fastened to the shaft 32. A shaft 36 is journaled in the hollow shaft 19, and has fastened thereto the Geneva wheel 35 and the sprocket drum 6. 85 The Geneva wheel can be engaged by the pin 34 of the disk 33.

An adjustable lever 38 with the elongated opening 38^a is fastened to the hollow shaft 19. A screw 39 passes through the opening 38^a and is threaded in the member 12, and by means of which the lever 38 is clamped in position. A shaft 40 is journaled in the members 11 and 12 and has fastened thereto a pinion 41, a grooved pulley 42 and the sprocket drum 7. The pinion 41 meshes with the spur gear 21. The grooved pulley 42 is connected by a belt not shown to a receiving reel not shown for the film 2. 95

Frames 69 and 70 are pivoted to the member 10 by means of the pivot 71. The frames 69 and 70 have respectively formed therewith the slotted extensions 69^a and 70^a, by which they can be clamped to the member 11, by means of the screw 74 and thumb nut 75. Presser rollers 69^b and 70^b are journaled in the frames 69 and 70 respectively. Springs 72 and 73 have each one end respectively fastened to the frames 69 and 70. The other ends of the springs 72 and 73 110 are fastened to the member 11 and thereby maintain the presser rollers 69^b and 70^b.

against the film which in turn is maintained in engagement with the sprocket drums 6 and 7.

A split sleeve 43 has formed therewith the extension 46 and the lugs 45 with the clamping screw 44. An elongated bearing 47 is supported in the extension 46 and has journaled therein the shutter shaft 48. A bevel gear 49 is fastened to one end of the shaft 48. The extension 46 has formed therewith a slot 77. A plate 78 is hinged by means of the hinges 78^a to the elongated bearing 47. Springs 79 encircle the hinge pins 78^b and one end of which bears against the sleeves 43 and the other end bears against the plate 70^a. The extension 46 with the slot 77 and plate 78 constitute a film guide. The extension 46 has a projecting aperture 80 and the plate 78 has a projecting aperture 81. The said apertures are axially in line with each other.

A shield 82 is connected to the plate 78 by means of the screws 83 and the separators 84. The extension 46 has connected thereto a lens barrel 53 which is shown in part. The lens barrel 53 has formed therewith the bearings 52 and 52^a, which have journaled therein the shaft 51 having the squared portion 51^a. A bevel gear 50 is slidably carried on the squared portion 51^a of the shaft 51, and a bevel gear 54 is fastened to one end of the shaft 51. The bevel gear 50 meshes with the bevel gear 49 and the bevel gear 54 meshes with the bevel gear 55. A yoke 56 is carried on the shaft 32 and holds the bevel gear 54 in mesh with the bevel gear 55. A sleeve 86 with the recess 90 has extending therefrom the segmental plate 85 and is loosely mounted on the shaft 48. A clutch sleeve 87 bears against the segmental plate 85, and therefore against the sleeve 86, and is held in position by the screw 88 in threaded engagement with shaft 48. A pin 91 is fastened in the elongated bearing 47 and engages the recess 90 of the sleeve 86.

The film 2 engages the sprocket drum 5 and passes through the film guide. The

film then engages the sprocket drum 6 from 50 which it passes over the sprocket drum 7.

The operation of the machine is evident from the construction and it need only to be stated, that by rotating the operating crank 20 the sprocket drums 5 and 7 are 55 continuously rotated while the sprocket drum 6 is intermittently rotated by virtue of the function of the Geneva wheel 35. In case the pictures on the film 2 are not in proper alignment with the projecting apertures 80 and 81, the sleeve 18 is raised or lowered by turning the hand wheel 18^a. By this means the film 2 is either raised or lowered as required.

Having thus described my invention, what 65 I claim as new and desire to secure by Letters Patent, is:

1. In a registering device for a moving picture machine the combination of a support, a vertical standard rigidly secured 70 to said support, a film guide having a projection aperture secured to said standard, means for feeding a film past said aperture, a frame for supporting said feeding means pivoted to said support and a vertically adjustable element on said standard connected to said frame.

2. In a registering device for a moving picture machine the combination of a support, a vertical standard rigidly secured 80 to said support, a film guide having a projection aperture secured to said standard, means for feeding a film past said aperture, a frame for supporting said feeding means pivoted to said support, a vertically movable member on said standard to which said frame is pivotally attached, and means for moving said member comprising a toothed rack on said standard, and a hand wheel provided with a pinion meshing with said 90 rack rotatably mounted on said member.

In testimony whereof I have signed my name in the presence of two witnesses.

EBERHARD SCHNEIDER.
